UNITED STATES PATENT OFFICE.

FREELAND W. OSTROM, OF BRIDGEPORT, CONNECTICUT.

SEWING-MACHINE.

SPECIFICATION forming part of Letters Patent No. 439,680, dated November 4, 1890.

Application filed August 28, 1890. Serial No. 363,279. (No model.)

To all whom it may concern:

Be it known that I, FREELAND W. OSTROM, of Bridgeport, county of Fairfield, State of Connecticut, have invented an Improvement 5 in Sewing-Machines, of which the following description, in connection with the accompanying drawings, is a specification, like letters on the drawings representing like parts.

This invention is an improvement on that 10 described in an application, Serial No. 250,802, the object of my invention being to simplify the construction and reduce the number of the parts. In the invention described in the said application the cutter-actuating rock- 15 shaft derives its movement to give the cutter-carrying bar a single thrust for each button-hole by or through a cast-off cam on the main shaft of the machine below the bed-plate; but in this my present invention I have provided 20 the rocking shaft which actuates the needle-bar with a pin or projection, and the cutter-actuating rock-shaft parallel to the said needle-bar-actuating shaft is provided with a latch, which is held out of engagement with 25 the said projection when the cutter-bar is in its normal position of rest; but when the button-hole is to be cut in the cloth held in the clamp under the needle the said cutter-bar-actuating rock-shaft is rocked sufficiently to 30 place the said latch in the path of movement of, and to be engaged by, the projection on the needle-bar-actuating rock-shaft, and the latter turns the cutter-bar-actuating rock-shaft and makes one depression or thrust of the 35 cutter-bar and cutter. While the cutter-bar-actuating rock-shaft is moving to throw the cutter-carrying bar down, a cam on the said rock-shaft acts to depress on an oscillating spring-supported lever having an arm, thus 40 disengaging it from a projection carried by the cloth-clamp-actuating disk or wheel, which projection at the proper time is acted upon to turn the said lever and start in operation the cutting mechanism.

45 Prior to my invention I am aware that a needle-bar-actuating rock-shaft has been connected with and adapted to impart a rocking motion to a cutter-bar-actuating shaft parallel to it by connections between said shafts, 50 one being in the shape of a ratchet-toothed hub, and the other a ratchet-toothed arm, as in application Serial No. 202,742, filed May

20, 1886; but in this present invention the clutch-box of the said application is dispensed with, and in its place I employ a latch, to be 55 described, which, after the cutter-bar-actuating rock-shaft has had given to it an initial movement by the oscillating lever herein described, causes said latch to engage a pin or projection carried by the needle-bar-actuating 60 rock-shaft.

One part of my invention consists in a button-hole sewing-machine containing the following instrumentalities—viz., stitch-forming mechanism, including a rock-shaft for actuating the needle-bar and provided with a pin or projection, a work-clamp, operating devices for the latter, an independent cutter-bar near the needle-bar, a cutter, an independent cutter-bar-actuating rock-shaft also 65 located above the bed-plate, the said cutter-bar-actuating rock-shaft being provided with a latch, a stop, and a cam, an oscillating lever, and means between it and the operating devices for the work-clamp to oscillate the 70 said lever and partially turn the cutter-bar-actuating rock-shaft in one direction and effect the engagement of its latch with the moving projection carried by the needle-bar-actuating rock-shaft to effect the descent of 75 the cutter-bar, the stop effecting the disengagement of the said latch from the said projection during the reverse movement of the cutter-bar-actuating rock-shaft, as will be described.

85 My invention also consists in an independent cutter-bar located at one side of the needle-bar, a cutter carried by the said cutter-bar, a cutter-bar-actuating rock-shaft located above the bed-plate, a latch carried by said 90 cutter-bar-actuating rock-shaft, and a stop co-operating therewith, combined with a needle-bar-actuating rock-shaft having a projection which is engaged at the proper time by the said latch, the said stop acting at a defined period during the reverse movements of 95 the said rock-shafts to lift the said latch from engagement with the said projection, thus leaving the cutter-actuating rock-shaft free from the control of the needle-bar-actuating 100 rock-shaft, substantially as will be described.

Other features of my invention will be hereinafter described and set forth in the claims.

Figure 1 is a rear side elevation of a button-hole-stitching machine embodying my invention; Fig. 2, a detail partial plan view of the bed-plate, the cloth-clamp-actuating devices, the vertical oscillating lever, and parts of the needle and cutter-bar-actuating rock-shafts; and Fig. 3, an enlarged partial section to the right of the dotted line x' , Fig. 1.

The bed-plate A, the guides or ways a , 10 cloth-clamp T U to hold the material under the needle-bar in position to be stitched and cut, the cloth-clamp-actuating mechanism, including a heart cam disk or plate, as E, a cam-slide M, and a feed wheel or disk F, the 15 lever H H', the main under shaft S, the link W, actuated by the lever H H' to rotate the feeding-disk step by step, are all substantially as in United States Patent No. 303,557, to which reference may be had.

20 The cam-hub B on the shaft S, the take-up R, actuated by it, the link B', actuated by an eccentric at one side of the said cam-hub, the needle-bar-actuating rock-shaft B², its crank B³, and link B⁴ to actuate the needle-bar B⁵, 25 (partially shown in Fig. 1,) are and may be all as common to the Wheeler & Wilson machine.

The cutter a' is attached to a cutter-bar adapted to slide in bearings in the head of 30 the machine near or parallel to the needle-bar. The cutter-bar has a collar a², provided with a backwardly and downwardly extended guiding-finger and stud 10, which is embraced by the slotted end of the arm b, fast 35 on the cutter-bar-actuating rock-shaft b', which is parallel to the shaft B² and above the bed-plate, the said shaft having a cam n and a collar n', provided with a finger n^x.

The stud m is erected above the center of 40 motion of the lever H H' and receives on it the oscillating lever m', having arms m⁵ and m⁷, and a projection m¹⁰ and a spiral spring m², fast at one end to a collar 20 and at its upper end to the lever m', and the arm m⁶, 45 attached to the cloth clamp-actuating-disk or wheel are or may be all substantially as in my application, Serial No. 250,803, where the said parts are more fully described.

The cutter-bar-actuating rock-shaft b' has 50 fast on it a collar r, on which at r' is pivoted a latch r², shown as acted upon by a spring r³, which acts to normally keep the said latch pressed against a stop 22, herein shown as forming part of the collar r. The spring r⁵ on the cutter-bar acts upwardly against the 55 knob r⁶ and lifts the cutter-bar, causing it by its collar a² to turn the rock-shaft b' and normally keep the finger n' against the arm m⁷ of the lever m', thus keeping the latch in the 60 position Fig. 3.

The spring m² acts normally to keep the pin 6 of the arm m⁷ against the stop m⁴ or upper bearing for the stud m and to keep the arm m⁵ pressed toward the rear of the 65 machine and up in the line of movement of the pin 24, carried by the arm m⁶, so that as the said pin in the rotation of the cloth-

clamp-actuating disk or wheel strikes the said arm, which it does, as herein provided for, just as the cutter-bar is to be actuated 70 for one thrust, and only one thrust, to cut the button-hole, preferably just after the stitching of two sides and one end has been completed, the said lever m' is turned, which causes the rock-shaft b' to be turned in the 75 direction of the arrow thereon, Fig. 3, which places the notched part of the latch in the range of movement of the pin or projection 25 of a collar 26, attached to the needle-bar-actuating rock-shaft, so that said projection 80 catches the said latch and completes the movement of the rock-shaft started by the lever m', acting on the finger n^x, and causes the cutter-bar to be thrown quickly down to make a cut in the cloth held by the clamp. 85 As the cutter-actuating rock-shaft b' is so turned to depress the cutter-bar to cut the material, the cam n, acting on the upper end of the lever m', depresses the same, the spring m² yielding until the arm m⁵ passes below the 90 pin 24 and releases arm m⁵, so that the spring m² by its expansion throws the arm horizontally back into the position from which it was moved by the projection 24, and said arm m⁵ cannot be again engaged to operate the 95 cutter until after another rotation of the cloth-clamp-actuating disk. The release of the arm m⁵ leaves the spring r⁵ free to lift the cutter-bar and turn the rock-shaft b' into its 100 normal position with the latch thrown out of the range of movement of the projection 25.

By "the reverse movement of the rock-shafts" I mean that movement of the needle-bar-actuating rock-shaft which takes place while the needle-bar is being elevated and that movement of the cutter-bar-actuating rock-shaft which takes place when the cutter-bar is rising.

I have described the spring r⁵ as employed to restore the rock-shaft b' to its normal position or to reverse its movement, and for this purpose I prefer to use some form of spring; but this invention is not intended to be limited to the exact location or construction of the said spring, and, in fact, such spring might 115 be altogether dispensed with, for while the projection 25 is moved on its backward stroke and the needle-bar is rising said projection will meet the shoulder 30 of the latch and reverse the movement of the rock-shaft b' or 120 return it into its normal position.

In the operation of my improved machine it will be seen that the latch r² is really disengaged from the projection 25 by the stop 22, which abuts against the said latch as the 125 rock-shaft b' is being reversed or turned back into its normal position, the said stop contacting with the said latch at a predetermined point in the oscillation of the two parallel rock-shafts, the said stop acting to swing the latch about a center coincident with the center of the rock-shaft b' instead of drawing the said latch longitudinally, as when the pin r' alone acts to move the latch. This posi-

tive swinging of the latch away from the projection 25 is an important feature of this invention.

I claim—

- 5 1. A button-hole sewing-machine containing the following instrumentalities, viz: stitch-forming mechanism including a rock-shaft for actuating the needle-bar and provided with a pin or projection, a work-clamp, operating devices for the latter, an independent cutter-bar near the needle-bar, a cutter, an independent cutter-bar-actuating rock-shaft, also located above the bed-plate, the said cutter-bar-actuating rock-shaft being provided with a latch, a stop, and a cam, an oscillating lever, and means between it and the operating devices for the work-clamp to oscillate the said lever and partially turn the cutter-bar-actuating rock-shaft in one direction and effect the engagement of its latch with the moving projection carried by the needle-bar-actuating rock-shaft to effect the descent of the cutter-bar, the stop effecting the disengagement of the said latch from the said projection during the reverse movement of the cutter-bar-actuating rock-shaft, substantially as described.
- 15 2. An independent cutter-bar located at one side of the needle-bar, a cutter carried by the said cutter-bar, a cutter-bar-actuating rock-shaft located above the bed-plate, a latch carried by said cutter-bar-actuating rock-shaft and a stop co-operating therewith, combined with a needle-bar-actuating rock-shaft hav-

ing a projection which is engaged at the proper time by the said latch, the said stop 35 acting at a defined period during the reverse movements of the said rock-shafts to lift the said latch from engagement with the said projection, thus leaving the cutter-actuating rock-shaft free from the control of the needle-bar- 40 actuating rock-shaft, substantially as described.

3. The rock-shaft B², having a collar and projection 25, means to actuate the rock-shaft, a rock-shaft b', parallel therewith and provided 45 with a collar and a stop 22, a cutter-carrying bar, means to connect it operatively with said shaft b', and a pivoted latch normally held out from engagement with the moving projection 25, combined with means to give to the 50 rock-shaft an initial movement to cause the said latch to engage the said projection and thereby cause the rock-shaft B² to move the rock-shaft b' for part of a stroke in one direction and partially backward in the opposite direction, the stop 22 acting during the 55 said backward movement of the rock-shaft b' to disengage the said latch from the said projection, as and for the purposes set forth.

In testimony whereof I have signed my 60 name to this specification in the presence of two subscribing witnesses.

FREELAND W. OSTROM.
